FOOT SUPPORTING BANDAGE

Filed Aug. 16, 1941

UNITED STATES PATENT OFFICE

2,358,966

FOOT SUPPORTING BANDAGE

Edward Einstoss, Chicago, Ill., assignor to The Scholl Mfg. Co. Inc., Chicago, Ill., a corporation of New York

Application August 16, 1941, Serial No. 407,125

3 Claims. (Cl. 128—166.5)

This invention relates to a foot supporting bandage, and more particularly to a bandage adapted to circumscribe a portion of the foot and lend support to adjacent parts of the foot, although the invention will have other and further advantages as will later appear.

In the past, many and various types of foot supporting devices, including those of the bandage type, have been produced but in most instances these formerly known devices were extremely difficult to place in proper position on the foot and just as frequently did not remain in proper adjustment or position on the foot after some walking by the user. Further, the types of bandage support heretofore known were, in most instances, "one-purpose" devices adapted only to provide support for a specific part of the foot. Such bandages, while giving some support to a certain part of the foot, were not adapted to also maintain adjacent parts of the foot in proper position. Hence, if the foot had become weakened, some portions of the foot might break down while the specific part was being aided or corrected.

Further, many of the devices heretofore known were not as sanitary as is desired, and in many cases after relatively short usage, and long before the device has shown actual wear, it would have to be discarded for sanitary reasons.

With the foregoing in mind, it is an important object of the instant invention to provide a foot supporting bandage which may be very easily slipped onto the foot in substantially similar manner to the insertion of a foot into a shoe, and which bandage will assume and retain a proper position on the foot indefinitely and without regard to the type of footwear worn.

It is also an object of this invention to provide a foot supporting bandage which may be readily and easily attached to the foot either inside or outside of an article of hosiery, and comfortably worn with the user's regular footwear, the structure being without bulk and fitting so intimately to the foot as to cause no discomfort to the user even with a shoe or other article of footwear commonly worn without a supporting bandage.

Still another important object of this invention is the provision of a foot supporting bandage not only designed to give adequate aid to a weakened or fallen longitudinal arch of the foot, but also adapted to simultaneously hold in proper position the structure of the tarsus and metatarsus in the event either of these parts of the foot are in a weakened condition.

A further object of the invention resides in 55 attached to the foot in a position to transversely

the provision of a foot supporting bandage made up of a pair of pieces of non-elastic material secured together in a manner to provide an open-sided pocket in which is removably inserted properly shaped means for supporting the longitudinal arch of the foot.

It is also a feature of this invention to provide a foot supporting bandage having a removable longitudinal arch supporting member, both said arch supporting member and the remainder of the bandage being easily laundered when desired.

Also an object of this invention is the provision of a foot supporting bandage comprising relatively thin non-elastic material having projecting portions thereon, which portions are connected by elastic ligaments so as to enable the bandage to embrace the foot, fit the foot intimately, and stay in position, arch supporting means being removably disposed within and carried by the bandage.

Still a further object of the invention resides in the provision of a foot supporting bandage arranged to lend support to the longitudinal arch between the first metatarsal head and the os calcis, and also to give a compression support to the tarsus and metatarsus, the bandage being easily placed in proper position on the foot, economically manufactured and used, and highly durable.

While some of the more salient features, characteristics and advantages of the present invention have been above pointed out, others will become apparent from the following disclosures, taken in conjunction with the accompanying drawing, in which:

Figure 1 is a fragmentary plan view of a human foot equipped with a foot supporting device embodying principles of the present invention;

Figure 2 is a fragmentary inside elevational view of the foot and bandage seen in Figure 1;

Figure 3 is an enlarged transverse sectional view through the foot and bandage, taken substantially as indicated by the line III—III of Figure 1, looking in the direction of the arrows;

Figure 4 is a fragmentary inside plan view of the bandage itself laid out in the flat, with parts broken away for purposes of better illustration; and

Figure 5 is a transverse vertical sectional view through the bandage, taken substantially as indicated by the line V—V of Figure 4.

As shown on the drawing:

In the illustrated embodiment of the present invention there is shown a supporting bandage attached to the foot in a position to transversely

embrace the foot in the region of the instep, a part of the bandage being anchored around the rear of the foot over the tendo-Achillis above the tuberosity of the os calcis, which anchorage better maintains the bandage in position on the foot without the necessity of binding the foot to the extent of discomfort.

With reference to Figure 4 it will be seen that in the illustrated instance the bandage is made up mainly of two separate pieces of material, of which an inner piece 10 is provided with a widened central region 11, and also with a pair of ears or tabs 12 and 13 extending from opposed portions of the widened central part 11. In this instance, the tabs 12 and 13 project substantially at right angles to each other. An outer piece 14 is also provided with a widened central portion 15, from which portion a pair of spaced ears or tabs 16 and 17 extend on one side, and a pair of spaced ears or tabs 18 and 19 extend from the opposite side, the tabs 18 and 19 having a slightly different angularity therebetween than the tabs 16 and 17 so as to enable better adjustment of the entire structure to the contour of the foot.

The material used in making the pieces 10 and 14 is preferably a relatively thin, non-elastic material which may be rendered impervious to moisture in any suitable manner if so desired.

The enlarged central portions 11 and 15 of the pieces 10 and 14, respectively, are joined together, in this instance, by stitching 20. It will be noted that the stitching 20 is in the form of a curvate line the end portions of which are turned in a reverse bend, as indicated at 21 and 22, thereby forming a substantially oval pocket between the bandage members 10 and 14. This pocket is open along one side edge, as indicated at 23, to permit the insertion of a longitudinal arch supporting member 24.

With reference more particularly to Figures 3 and 5 it will be seen that in the illustrated instance the arch supporting member 24 is preferably of resilient material such as rubber, sponge rubber, latex, or the equivalent. It will also be noted that the member 24 is thickest at the point ultimately disposed immediately beneath the inner high point of the longitudinal arch, namely, beneath that portion of the longitudinal arch farthest from the ground when the foot is in normal standing position. From this thickest area or region the member 24 tapers in all directions to a relatively thin edge. The member 24 also has a somewhat curvate shape, as seen best in Figure 3, so that it not only fits beneath the plantar surface of the longitudinal arch but also embraces a portion of the inner side wall of the foot in the region of the longitudinal arch.

In Figures 1, 2 and 3 the bandage support is seen in association with a foot 25, and with reference to Figure 3, the disposition of the arch supporting member 24 is best seen. It will be noted that the positioning and shape of this arch supporting member is such as to afford adequate support throughout the entire width of the inner longitudinal arch of the foot.

In order to maintain the bandage in intimate association with the foot and in the proper location on the foot, suitable elastic or stretchable ligaments are employed. The projecting tab 12 of the inner piece 10 and the projecting tab 16 of the outer piece 14 are joined together by an elastic ligament 26. Likewise, the projecting tabs 17 and 18 of the outer piece 14 are joined by an elastic ligament 27. The remaining tab 13 of the inner member and the remaining tab 19 of the

outer member are joined by a somewhat longer elastic ligament 28. With such elastic ligaments joining opposed or substantially oppositely disposed projections, the entire bandage is given such a shape as to enable it to circumscribe the instep portion of the foot. The ligaments 26 and 27 extend over the top of the instep. In order to insure easy application of the bandage and also to give added assurance of the bandage staying in proper position on the foot without undue binding of the foot, the longer ligament 28 is disposed around the rear of the foot, as seen best in Figures 1 and 2, passing over the tendo-Achillis above the tuberosity of the os calcis. Due to the elasticity of the various ligaments 26, 27 and 28, the supporting bandage is intimately fitted around the foot, not sufficiently tightly to cause discomfort to the user, but sufficiently tightly to aid materially in maintaining and holding the structures of the tarsus and metatarsus of the foot in proper position. Thus, while treatment and support tending to restore a weakened or fallen longitudinal arch of the foot is adequately provided, at the same time a weakened tarsus and metatarsus are also given aid and prevented from assuming any maladjusted position.

It is a simple expedient to place my novel supporting bandage in proper position upon the foot, either beneath or outside an article of hosiery.

30 The foot is slipped through the bandage, beneath the ligaments 26 and 27 in the manner in which a shoe is placed upon the foot, and then the ligament 28 is drawn over the heel of the foot to the position seen in Figure 2. Once in position upon 35 the foot, the bandage will remain there, regardless of the type of footwear worn by the user, or regardless of the user's activity, until the bandage is intentionally removed.

It will also be noted that by virtue of the character of the material forming the bandage, the entire bandage may be readily laundered or sterilized. This is facilitated by the fact that the arch supporting member 24 may be easily removed 45 from the pocket between the pieces 10 and 14 and again reinserted in the pocket after the cleansing operation is completed.

It is further apparent that the thinness of the bandage, the only thick portion being the supporting member 24, which is disposed beneath 50 the arch portion of the foot, makes it possible for the bandage to be worn comfortably in articles of footwear with which no bandage previously known could be worn. This thinness and lightness of the bandage also makes it possible to conveniently carry the bandage around and have it 55 available wherever the user may travel, since it is easily folded into small, compact form, readily insertable in a pocket, hand-bag, pocketbook or the like, in the event the user does not require the bandage at all times, but perhaps only upon 60 occasions of unusually strenuous exercise or infrequent exertion.

From the foregoing, the economy, facility and durability of the bandage of my invention will be 65 apparent.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. In an arch supporting bandage, a pair of 75 pieces of material having widened intermediate

portions arranged in superposed relationship and secured together, arch supporting means carried by said superposed portions, each of said pieces having tabs projecting therefrom, and means connecting the tabs of one piece with the tabs of the other piece to permit said bandage to transversely circumscribe the foot.

2. In an arch supporting bandage, a non-elastic fabric member having a widened intermediate portion and a pair of spaced tabs extending from each of opposite sides of said widened portion, a second non-elastic member having a widened intermediate portion with a single tab extending from each of opposite sides of said widened portion, said widened portions being superposed and stitched together to provide a pocket, arch supporting means in said pocket, and elastic means joining the two tabs of the second member to two

tabs of the first member and joining the remaining tabs of the first member to provide a bandage capable of circumscribing the foot.

3. In an arch supporting bandage, a non-elastic member having a widened intermediate portion and a pair of spaced tabs extending from each of opposite sides of said portion, a second non-elastic member having a widened intermediate portion with a pair of spaced and angularly disposed tabs extending therefrom, said widened portions being superposed with one disposed transversely to the other and secured together, an arch supporting element between said portions, and elastic ligaments joining the tabs of the second member to tabs of the first member and joining the remaining tabs of the first member to each other.

EDWARD EINSTOSS.
